UNITED STATES PATENT OFFICE.

HENRY W. BRECKENRIDGE, OF PROVIDENCE, RHODE ISLAND, ASSIGNOR
TO JOSEPH A. MILLER, TRUSTEE, OF SAME PLACE.

TELEPHONE-SWITCH.

SPECIFICATION forming part of Letters Patent No. 278,494, dated May 29, 1883.

Application filed April 24, 1882. (No model.)

To all whom it may concern:

Be it known that I, HENRY W. BRECKENRIDGE, of the city and county of Providence, and State of Rhode Island, have invented a new and useful Improvement in Telephone-Switches; and I hereby declare that the following is a full, clear, and exact description of the same, reference being had to the accompanying drawings, forming part of this specification.

This invention has reference to an improvement in pegs for connecting the line-wires with the bars of a telephone switch-board; and it consists in the peculiar construction of the peg by which metallic contact is secured first with the wire and then with both sides of the bar, so that a continuous circuit is formed, as will be more fully set forth hereinafter.

Figure 1 is a view of a portion of a telephone central-office switch-board. Fig. 2 is a sectional view, shown full size, showing the peg connecting the wire with the bar on the switch-board. Fig. 3 is a transverse sectional view.

In the drawings, *a a a* are line-wires. *bbb* are the bars of the switch-board. *c* is the improved peg, provided at its upper end with the flattened sides *d*, the lower tapering end being split, so as to form the bifurcated ends *f* and *g*, forming springs. The slit is made a little less in width than the thickness of the wire, so that when pushed over the wire the ends *f* and *g* will spread apart, and, on entering the hole in the bars *b*, will be forced in contact with the sides of the holes, thus insuring absolute metallic contact first with the wire and then with the two sides of the hole in the bar *b*. By this arrangement not only is the wire brought in metallic connection with the bar, but two separate connections are made by the two legs *f*

and *g*, thus making a more complete electric circuit than when only one connection is made. The ends of the legs *f* and *g* are rounded, so as to enlarge the opening of the slit and guide the peg automatically over the wire, thereby facilitating the insertion of the peg. In placing the peg over the wire connection is first made with the wire, and in pushing the same into any one of the holes the metallic connection with the bars is made gradual. The whole construction is simple and cheap, the metallic contact perfect, and the connection can be quickly made.

Having thus described my invention, I claim as new and desire to secure by Letters Patent—

1. The combination, in a telephone central-office switch-board, of the bars *b*, arranged parallel with each other and provided with perforations, the parallel wires *a*, supported opposite the perforations of bars *b* and a little distance from said bars, and the solid peg slit-ted at its tapering end to form spring-legs *f* and *g*, said legs being adapted to be first sprung over a wire and then into a perforation in one of the bars to make contact between said wire and bar through each of the spring-legs, substantially as described.

2. A peg for establishing contact between the wires and bars of a switch-board, consisting of a solid metallic body the tapering end or point of which is divided at its axial center by a longitudinal slit to form tapering spring-legs of equal length, substantially as described.

HENRY W. BRECKENRIDGE.
